[57] CLAIM

The ornamental design for a combined vehicle cab and roll bar safety cage, as shown and described.

DESCRIPTION

FIG. 1 is an exploded perspective view of a combined vehicle cab and roll bar safety cage showing my new design;

FIG. 2 is a rear elevation view of the vehicle cab thereof shown separately for convenience of illustration;

FIG. 3 is a front elevation view of FIG. 2;

FIG. 4 is a side elevation view of FIG. 2;

FIG. 5 is an opposite side elevation view of FIG. 2;

FIG. 6 is a top plan view of FIG. 2; and,

FIG. 7 is a bottom plan view thereof.

FIG. 5

FIG. 7

FIG. 2

FIG. 4

FIG. 6
